APPLIANCE FOR PRESSING NECKTIES
OR STRIP MATERIAL

John Siddons Corby, Old Windsor, England

Application April 17, 1951, Serial No. 221,408

Claims priority, application Great Britain
April 18, 1950

2 Claims. (Cl. 38—11)

1

This invention relates to an appliance for pressing neckties, ribbons, collars, waist belts, or other similar wearing apparel, so as to press or flatten out creases or the like in these articles or to restore them to their original flat shape.

According to the present invention an appliance for the purpose described is provided with a supporting structure in which are mounted two rollers, which are connected together by a strip of flexible material adapted to be unwound from one roller and wound on the other roller, one of the rollers being spring-actuated so as to return both rollers to their starting position, while the other roller is arranged for manual rotation, a spring actuated member bearing against the strip of flexible material wound on the second-mentioned roller for retaining the roller in any position into which it has been moved and for pressing upon an article wound up between the folds of the flexible material, said spring actuated member when moved away from its roller enabling the two rollers to be returned to their respective normal position.

The spring acting on the spring actuated roller is preferably located in the interior of this roller in a similar manner to the spring of a spring-roller blind.

The spring actuated member is preferably in the form of a lever hingedly mounted at one end in the supporting structure, while its other end bears against the manually operable roller, a spring acting on said lever between the pivot axis of said lever and the roller against which it is adapted to bear.

The invention will now be described by way of example with reference to the accompanying drawings, wherein:

Fig. 1 is a front elevation of a press for ties and other similar wearing apparel.

Fig. 2 is a plan view of Fig. 1.

Fig. 3 is a rear view of Fig. 1.

Fig. 4 is an underside plan of Fig. 1.

Fig. 5 is a view of Fig. 1 looking at the right hand end thereof.

Fig. 6 is a section on the line VI—VI of Fig. 1.

As shown in the drawings, an appliance, for the purpose described, is provided with supporting means which may be formed by two side plates 1, 2 of metal, wood or other suitable material held spaced apart by a number of rods such as 3, 4, 5, 6.

Between the two side plates 1, 2 are mounted two spindles 7, 8 the spindle 7 being fixedly mounted in the side plates 1, 2 whilst the spindle 8 is rotatably mounted in the side plates 1, 2.

2

On each spindle 7, 8 is mounted a roller 9, 10 preferably of wood or other suitable material.

The roller 10 on the fixed spindle 7 is free to turn relatively to its spindle 7 to which it is connected by a coiled spring 11, one end of the spring 11 being secured to the roller 10 at 12 and the other end is secured to the spindle 7 at 13. The connection between the fixed spindle 7 and the roller 10 mounted thereon is preferably similar to the arrangement of a spring-roller blind.

The roller 9 is secured to its spindle 8, for example by one or more spiders 14. The spindle 8 projects from one or both of the side plates 1, 2, the projecting end or ends of the spindle having an operating knob 15 or lever secured thereto so as to facilitate turning of the spindle 8 and thus of the roller 9.

To the two rollers 9, 10 are respectively secured the opposite ends of a strip 16 of flexible material, such as canvas.

The securing is preferably effected by passing the corresponding end of the strip 16 at least once around the corresponding roller 9, 10 and then securing it to the adjacent portion of the strip 16. The securing may also be effected by adhesive.

The roller 9 is preferably located uppermost, and the lower roller 10 is preferably located forwardly of the upper roller 9 as shown in Fig. 6.

The spacing between the rollers 9, 10 is such that an article to be operated upon can pass between the layers of the strip 16 while these are being rolled on to the manually operated roller 9, while also being capable of being rolled around the upper roller 9 one or more times.

Against the upper roller 9 bears a spring-actuated member 17 which is pivotally mounted on the rod 6 mounted in the side plates 1, 2 rearwardly of the lower roller 10.

The spring-actuated member 17 is preferably in the form of a lever on which is fitted a rod 18 hinged at its lower end on the rod 6 hingedly mounted on the rod 6. The lever 17 bears at its upper end against the upper roller 9, while a spring 20 is anchored at one end to the lever 17 about midway of its length, the other end of the spring 20 is anchored to a rod 21 mounted in the side plates 1, 2. The pressure of the spring actuated lever 17 against the upper roller 9 normally prevents movement of the latter.

The operation of the device above described, assuming that the lower roller 10 has been turned by its spring 11 so that the strip of flexible material 16 has been wound as far as possible thereon, is as follows:

The end of the article to be treated has the end thereof placed against the strip of material 16 at a point between the two rollers 9, 10 and the upper roller 9 is turned by means of the knob 15 or the like so as to wind the flexible material 16 and simultaneously wind the article around the upper roller 9 within the convolutions of said flexible material and to unwind the flexible material from the lower roller 10 while winding up the spring 11 of the latter. The action of the spring actuated lever 17 is such that it permits of this movement but does not prevent rotation of the upper roller 9 when actuated by the knob 15 or the like. When the flexible material 16 has been unwound from the lower roller 10 to the full extent, the article may have been fully or partly wound around the upper roller 9 and is thus pressed.

To release the article the spring actuated lever 17 is pulled away from the upper roller 9 thus allowing the spring 11 of the lower roller 10 to turn in the direction opposite to that produced by turning the upper roller 9 as above described, so that the flexible material 16 is wound on to the lower roller 10 and the article gradually released from the appliance.

Should the article, such as a necktie, be of a length greater than the length of flexible material 16 which is wound from the lower roller 10 on to the upper roller 9, one end of the article is first treated and then the other, or the article may be folded and thus its whole length treated.

By passing an article into the appliance it is pressed and rolled and creases are removed therefrom.

The spring pressed lever 17 is preferably of a width so as to extend over a predetermined length of the upper roller 9 so that it also applies pressure to the article which is being treated in the appliance.

As a result of passing the article around a roller such as 9, it is spread, this action assisting in smoothing out a crumple or crease, while at the same time pressure is also applied to the article by the spring actuated member.

Since certain modifications may be made in the device of the present invention without departing from the scope thereof, it is intended that all matter contained in the foregoing description and shown in the accompanying drawings be interpreted merely as illustrative and not in a limiting sense.

Having thus described the invention what is new and desired to be obtained by Letters Patent,

1. A pressing appliance comprising supporting means, two rollers mounted on said supporting means, said rollers being connected together by a strip of flexible material, said strip of material being attached at its opposite ends to a respective roller and adapted to be unwound from one of said rollers and wound on the other of said

rollers and rewound on said first-mentioned roller, one of said rollers being spring-biased in a direction tending to return said roller to its starting position, the other of said rollers being arranged for manual actuation, a spring actuated member disposed for releasable abutment against said strip of flexible material when wound on said second-mentioned roller for retaining the latter in a predetermined manually adjusted position and serving additionally for pressing upon an article wound up between the convolutions of said flexible material, said spring actuated member being arranged for releasing its respective roller when moved away from the latter, thereby enabling said spring-biased roller to be returned to its normal position in order to simultaneously wind said strip thereon and unwind said strip from said other roller while the latter returns to its normal position.

2. A pressing appliance comprising supporting means, two rollers mounted on said supporting means, said rollers being connected together by a strip of flexible material, said strip of material being attached at its opposite ends to a respective roller and adapted to be unwound from one of said rollers and wound on the other of said rollers and rewound on said first-mentioned roller, one of said rollers being spring-biased in a direction tending to return said roller to its starting position, the other of said rollers being arranged for manual actuation, a spring actuated member disposed for releasable abutment against said strip of flexible material when wound on said second-mentioned roller for retaining the latter in a predetermined manually adjusted position and serving additionally for pressing upon an article wound up between the convolutions of said flexible material, said spring actuated member being arranged for releasing its respective roller when moved away from the latter, thereby enabling said spring-biased roller to be returned to its normal position in order to simultaneously wind said strip thereon and unwind said strip from said other roller while the latter returns to its normal position, said spring-actuated member comprising a lever pivotally mounted at one end in said supporting means and having its opposite end disposed for engagement against said manually operable roller, and spring means for normally maintaining said lever in operative abutment against said manually operable roller.

JOHN SIDDONS CORBY.
